UNITED STATES PATENT OFFICE.

FRANK L. WHITAKER, OF OLNEY, ILLINOIS.

TELEPHONIC ELECTRODE AND METHOD OF CONSTRUCTING SAME.

Application filed June 11, 1921. Serial No. 476,795.

To all whom it may concern:

Be it known that I, FRANK L. WHITAKER, a citizen of the United States, residing at Olney, in the county of Richland and State of Illinois, have invented certain new and useful Improvements in Telephonic Electrodes and Methods of Constructing Same, of which the following is a specification.

This invention relates to an improved electrode for microphonic telephone transmitters and the method of constructing the same.

In the usual construction of microphonic transmitters the variable transmission unit comprises one or more vibratory electrodes in electrical contact with a loose granular conducting substance, such for example as carbon, interposed between them and variable in the resistance which it affords to the passage of the electric current in ratio to the degree to which it is compressed by the vibration of the electrode between which it is interposed. Such a variable resistance unit however presents the disadvantage that the loose granular substance is liable to be compacted by the smooth surfaces of the electrodes thus detracting from the efficiency of the unit, or the granular substance is liable to become displaced with a like result. One of the primary objects of the present invention is therefore to provide, in a variable resistance unit, an electrode differing from the ordinary smoothly surfaced electrode usually employed in that provision is made for a more intimate contact between its surface and the particles of the granular resistance substance of the unit, the electrode being further so constructed as to provide for an electrical contact surface of maximum effective area.

A further object of the invention is to provide an electrode so constructed as to eliminate likelihood of packing of the loose granular material and likelihood of displacement of this material in any manner liable to detract from the efficiency of the unit.

A further object of the invention is to evolve a novel method whereby the electrode possessing the above-mentioned characteristics may be economically produced.

In the accompanying drawings:

Figure 1 is a perspective view illustrating the button or mount of the electrode in its initial condition;

Figure 2 is a diametric section therethrough;

Figure 3 is a view similar to Figure 1 illustrating the first step in the preferred method of constructing the electrode;

Figure 4 is a diametric section through the electrode at the completion of the step illustrated in Figure 3;

Figure 5 is a view similar to Figure 4 illustrating the next step in the method;

Figure 6 is a perspective view of the completed electrode;

Figure 7 is a diametric sectional view through the completed electrode;

Figure 8 is a perspective view illustrating a slightly different method;

Figure 9 is a diametric section through an electrode completed in accordance with the step illustrated in Figure 8.

The drawings illustrate two forms of electrode and disclose two methods of producing such an element.

The electrode embodying the invention consists essentially of a cupped button which is indicated in general by the numeral 1 and which comprises a circular disk 2 of any metal or composition of metals found suitable for the purpose and provided with an upstanding peripheral flange 3 so that the face of the button is provided with a shallow cavity 4. A threaded shank 5 is provided upon the opposite face of the disk 2 and affords means whereby the disk or button may be mounted in the usual manner. At this point it may be stated that while the button in the illustrated embodiment of the invention is in the form of a flat circular disk, the principles of the invention are applicable to electrodes having various other shapes and constructed in various other forms. The first step in the method for producing the electrodes shown in Figures 6 and 7 is illustrated in Figures 3 and 4 and consists in roughening the surface of the disk 2 from which the flange 3 projects and as indicated by the numeral 6, this being done in any convenient manner as for example by the use of a sand blast although this surface might be etched by acid or in fact roughened in any other manner found expedient. After the disk has been rough-surfaced in the manner illustrated in Figures 3 and 4, there is introduced into the cavity 4, and preferably uniformly spread, a thin layer 7 of a cementing or bonding material. Various materials may be employed for this purpose and the invention is not in fact limited to any particular ma-

terial. For example use may be made of dry shellac, the various jewelers' cements, baking japans, certain sealing waxes, certain kinds of glazes, or even certain metal alloys. Having supplied the layer 7 of the cementing or bonding material, a quantity of carbon granules indicated by the numeral 8 is applied or deposited within the cavity, the granules being spread or arranged as evenly as possible over the layer 7 as best shown in Figure 5. Pressure is then applied to the layer of granules, and simultaneously, the assemblage is subjected to heat at a sufficiently high temperature to melt or fuse the cementing or bonding material 7, whereupon, by reason of the application of pressure, the granules 8 will be forced firmly into contact with the roughened surface 6 of the disk 2, and the entire mass of granules will be brought to a substantially level surface at the top of the cavity 4. Upon permitting the assemblage to cool, the cementing or bonding materials 7 will harden, and the carbon granules will become firmly and securely embedded therein and in electrical contact with the roughened surface of the disk 2, the article in its completed form being shown in Figures 6 and 7. Carbon is preferably the granular substance employed and it is this material that is likewise used in loose form in electrical contact with the electrode in the completed variable resistance unit as established in a microphonic transmitter. By roughening the surface of the disk the carbon particles or granules 8 are brought into more intimate contact therewith, and likewise a more firm or secure union is effected by the component parts of the electrode than would be the case if this surface were smoothly finished.

In that embodiment of the invention illustrated in Figures 8 and 9 of the drawings, instead of roughening the surface of the disk 2, a circular disk or sheet 9 of fine metal gauze may be arranged within the cavity 4 of the button 1 and serves the same purpose as the roughened surface 6 of the disk comprising the button, it being under-

stood that the method of procedure is otherwise the same as above described. 50

From the foregoing description of the invention it will be evident that the contact surface of an electrode constructed in accordance with the invention is of a rough or irregular contour as distinguished from the smooth contact surface of the metal or carbon electrodes heretofore employed and that thus there is a more intimate electrical contact between the surface and the loose carbon particles, and also there is no likelihood 55 of the loose particles becoming compacted.

By providing the cavity 4 in the face of the button 1 the granules 8 are confined within the bounds of the periphery of the button and are prevented from being forced over the edge and weakening the bond between the parts at this point. Also by this means the granules are prevented from being chipped off if the button is subjected to rough handling prior to installation in the 60 transmitter.

Having thus described the invention, what is claimed as new is:

1. The method of producing an electrode for a variable resistance unit which comprises distributing upon the surface of a conducting base a layer of cementing or bonding material, distributing upon said layer a quantity of conducting granules, and subjecting the assemblage to heat and pressure to embed the granules in the cementing or bonding material in electrical contact with the surface of the base. 75

2. The method of producing an electrode for a variable resistance unit which comprises preparing a conducting base with a roughened surface, distributing upon the surface a layer of cementing or bonding material, distributing upon the said layer a layer of conducting granules, and subjecting the assemblage to heat and pressure to embed the granules in the cementing or bonding material in electrical contact with the said surface of the base. 80 85 90

In testimony whereof I affix my signature. 95
